UNITED STATES PATENT OFFICE.

SAMUEL D. McMILLAN, OF LEXINGTON, NORTH CAROLINA.

CHECK AND TICKET STAMP.

1,371,798.

Specification of Letters Patent. Patented Mar. 15, 1921.

Application filed December 8, 1920. Serial No. 429,150.

To all whom it may concern:

Be it known that I, SAMUEL D. McMILLAN, a citizen of the United States, residing at Lexington, in the county of Davidson 5 and State of North Carolina, have invented a new and useful Check and Ticket Stamp, of which the following is a specification.

It is the object of this invention to provide a device for stamping baggage checks, 10 tickets and the like, so constructed that type carrying members may be presented one after another for operation thereby rendering it unnecessary for the operator to pick up and lay down a plurality of separate 15 rate stamps.

The type carrying members are mounted on a rotor, and the invention aims to provide means whereby the rotor may be held in any desired position, releasably, thereby 20 presenting any type carrying member in operative position.

The type carrying members on the rotor coöperate with a ribbon, and one object of the invention is to provide novel means 25 for feeding, controlling and operating the ribbon.

It is within the province of the disclosure to improve generally and to enhance the utility of devices of that type to which the 30 invention appertains.

With the above and other objects in view, which will appear as the description proceeds, the invention resides in the combination and arrangement of parts and in the 35 details of construction hereinafter described and claimed, it being understood that, within the scope of what is claimed, changes in the precise embodiment of the invention shown can be made without departing from 40 the spirit of the invention.

In the accompanying drawings:—

Figure 1 shows in front elevation, a device constructed in accordance with the invention, one of the hoods being broken 45 away; Fig. 2 is a rear elevation; Fig. 3 is a section taken on the line 3—3 of Fig. 4, parts being left in elevation; Fig. 4 is a section taken on the line 4—4 of Fig. 3; Fig. 5 is an elevation showing one end of 50 the shaft; Fig. 6 is an elevation showing

the opposite end of the shaft; Fig. 7 is an elevation illustrating one of the feed pawls and attendant parts; Fig. 8 is a perspective view depicting the brake springs.

The device forming the subject matter 55 of this application embodies a frame, denoted generally by the numeral 1. The frame 1 is a composite structure, comprising a base 2 and a standard 3 in the form of a plate, the standard 3 being supplied at 60 its upper end with a forwardly presented bracket 4. A lug 5 is fashioned integrally with the bracket 4 and with the standard 3 and projects rearwardly from the standard. In the lower surface of the bracket 65 4, a recess 6 of rectangular outline is formed.

A dial 7 is located parallel to the standard 3 and includes a foot 8 attached by securing elements 9 to the base 2. The dial 70 7 is supplied with a forwardly extended annular flange 10 provided with seats or notches 11. On the outer surface of the dial 7 are radial inscriptions 12. If the device is to be used in a railroad office, the 75 inscriptions 12 may be in the form of names of stations.

A shaft 14 is journaled for rotation in the standard 3 and in the dial 7. The rear end of the shaft 14 is provided with a 80 squared end 16 from which a threaded stem 26 projects. A hand wheel 15 fits on the squared end 16 of the shaft 14 and is held thereon by a nut 36, threaded on the stem 26. On its forward end, the shaft 14 carries an elongated shoulder 17 from which 85 a threaded stem 18 projects.

The numeral 19 denotes an arm adapted to move over the dial 7, the inner end of the arm being mounted on the shoulder 17 90 of the shaft 14. The arm 19 is offset, as shown at 20, so that the outer end of the arm may clear the flange 10 on the dial 7. A disk 21 is carried by the threaded stem 18 and bears against the inner end of the 95 arm 19 to hold the arm on the shoulder 17 of the shaft 14, the disk having a flange 22 projecting toward the dial 7 and of annular form, the flange having a notch 23 wherein the arm 19 is received, a secure 100

connection between the disk and the arm thus being afforded. The disk 21 is held in place by a nut 24 mounted on the threaded stem 18 of the shaft. Adjacent to its outer 5 end, the arm 19 is provided with an opening 25. A resilient latch 27 extends longitudinally of the arm 19, one end of the latch being attached by a securing element 28 to the arm. The latch 27 includes a finger 10 29 movable in the opening 25 of the arm 19 and adapted to coöperate with the seats or notches 11 which are fashioned in the flange 10 of the dial 7.

A rotor 30 is located between the standard 15 3 and the dial 7 and is mounted on the shaft 14. The shaft 14 carries a cross pin 31 received in a seat 32 formed in the rotor 30, to the end that when rotation is imparted to the shaft 14, the member 30 will be rotated likewise. The rotor 30 is equipped in its periphery with radial slots 33 in which wedge-shaped type bars 34 are seated, each type 20 25 bar having a lateral flange 35 overlapping the periphery of the rotor. Ribs 37 are formed integrally with the type bars 34 and with the flanges 35 of the type bars, and aid in holding the type bars in the slots 33 of the rotor. On the outer ends of the type 30 35 bars 34 are located type 38. The type 38 on each bar 34 spells out one of the inscriptions 12 on the dial 7.

The machine includes a plunger 39, the plunger embodying a foot 40 shaped to fit slidably in the recess 6 of the bracket 4, the 35 foot being held in the recess against rotation, so that the foot 40 on the plunger will always be presented parallel to the type bars 34, when the type bars are presented, one after another, to the foot 40, when the 40 member 30 is rotated. The foot 40 is provided with a retainer 41 having flanges 42 holding a platen 43, which may be made of rubber, the platen being adapted to co-operate with the type bars 34. The plunger 45 45 50 embodies a stem 44 connected to the foot 40 and mounted to slide in the bracket 4, the stem having a button 45 at its upper end.

The forward end of an arm 46 receives 50 the stem 44. A compression spring 47 surrounds a portion of the stem 44 and abuts at its lower end against the bracket 4, the upper end of the spring abutting against the arm 46. The spring 47 serves a double 55 function, in that it constitutes means for retracting the plunger 39, and constitutes, also, means for effecting a part of the ribbon feeding mechanism, to be described hereinafter. There is a socket 48 on the outer 60 end of the arm 46, wherein a slide 49, preferably in the form of a rod, is held. The slide of rod 49 is mounted for reciprocation in the lug 5 on the standard 3.

Levers 50 are mounted on the standard 65 3 through the instrumentality of fulcrum

members 51, the inner ends of the levers 50 being loosely pivoted to the lower end of the slide 49, as indicated at 52. Supports 53, in the form of strips, are held on the standard 3 by the fulcrum members 51 which 70 carry the levers 50. The supports 53 include angular portions 54, the extremities of which rest upon the edge of the dial 7, as indicated at 55, so as to stiffen the supports 53.

Shafts 56 are journaled for rotation in the supports 53 and in the angular portions 54 thereof. The ends of a ribbon 57 are wound about the shafts 56, the ribbon passing between the rotor 30 and the foot 40 80 of the plunger 39, in contact with those of the type bars 34 which happen to be at the top of the rotor. The ribbon 57 of course, constitutes means whereby the ink is presented to the type bars 34. The ribbon 57 is 85 covered in part by hoods 58 carried by the parts 54 of the support 53, the hoods being separated, as shown in Fig. 1, so that the platen 43 may operate therebetween, when the plunger 39 is thrust downwardly. Knobs 90 59 are mounted on the forward ends of the shafts 56. Bowed spring strips 60 are provided, the strips having openings 61, and being provided, at one end, with outstanding fingers 62. Abutments 63 are mounted on 95 the shafts 56. The shafts 56 pass through the openings 61 in the strips 60, the ends of the strips 60 bearing on the supports 53, the fingers 62 receiving the supports 53, to prevent the spring strips 60 from rotating 100 with the shafts 56. The intermediate portions of the strips 60 bear against the abutments 63 on the shafts 56, the strips constituting spring brakes, controlling the rotation of the shafts 56 and preventing back-lash or looseness in the ribbon 57.

Ratchet wheels 64 are mounted on the rear ends of the shafts 56 and are engaged by pawls 65 pivoted at 66 on the outer ends of the levers 50. Springs 67 are secured to the levers 50 and engage the pawls 65, the pawls being constrained by the springs to co-operate with the ratchet wheels 64. Each pawl 65 is supplied at its rear end with a projection 68. Shafts 69 are journaled in 115 the levers 50 and are accessible from the rear end of the structure, as indicated in Fig. 4. Each shaft 69 has a radially extending detent 70, adapted to be moved into and out of engagement with the projection 68 on the 120 corresponding pawl 65.

In practical operation, rotation is imparted to the shaft 14 and to the member 30 by way of the hand wheel 15. In this way, any desired one of the inscriptions 12 may 125 be brought to the top of the rotor 30, the corresponding type bar 34 being positioned beneath the platen 43. The finger 29 on the spring latch 27 clicks into and out of the seats 11 in the flange 10 of the dial 7 and, 130

ultimately, arriving in one of the seats, holds the rotor 30 against movement and maintains the selected type bar 34 beneath the platen 43 of the plunger 39. The ribbon 57, 5 as hereinbefore explained, rests on the type bar 34 which has been brought into operative position. A ticket or other object is inserted between the ribbon 57 and the platen 43, whereupon the plunger 39 is thrust 10 downwardly by pressure exerted on the button 45, the spring 47 being compressed. By this operation, the inscription carried by the selected type bar 34 is imprinted on the ticket. When the platen 45 is released, the 15 plunger 39 moves upwardly under the impulse of the spring 47.

From the foregoing it will be obvious that one of the inscriptions 12 after another may be brought readily into operative position, 20 it being unnecessary to fish above for separate stamps, ink them, apply them to the ticket or other object, and replace the stamps in a rack, after the common and present custom.

25 When the plunger 39 is pressed downwardly, the arm 46 and the slide 49 are carried downwardly by the button 45. The levers 50 are tilted on their fulcras 51 and the pawl 65 on one lever coöperates with the 30 corresponding ratchet wheel 64 and rotates the adjacent shaft 56, the ribbon 57 being fed along by this procedure. Either of the pawls 65 may be swung backwardly out of engagement with the corresponding ratchet 35 wheel 56, the shaft 69 being rotated until the detent 70 coöperates with the projection 68 of the pawl, to hold the pawl out of engagement with the ratchet wheel 64, as shown at the left hand side of Fig. 2. Since 40 there are two pawls 65, and in view of the fact that either pawl may be operated to the exclusion of the other, the ribbon 57 may be fed in one direction and then in an opposite direction. At any time, rotation may be im- 45 parted manually to the shafts 56, by way of the knobs 59, for the purpose of moving the ribbon 57. The strips 60 move the shafts 56 endwise and press the knobs 59 against the hoods 58, a spring brake thus being pro- 50 vided, and backlash or looseness in the ribbon 57 being avoided.

Owing to the fact that the standard 3 is provided with the lug 5 which receives the slide 49, and owing to the way in which the 55 arm 46 is mounted on the stem 44, there are no rearwardly projecting levers in the feeding mechanism, the compactness and strength of the device being enhanced accordingly.

60 There may be any desired number of the wedge-shaped type bars 34, the inscriptions 12 being increased or decreased accordingly. When it is desired to renew or change one of the type bars 34, the type bar may be 65 prized out of the rotor, through the instru-

mentality of a tool of any desired sort, inserted beneath the flange 35.

Having thus described the invention, what is claimed is:

1. In a device of the class described, a 70 frame comprising a standard having a forwardly presented bracket; a type-carrying rotor journaled on the standard below the bracket; a plunger slideable in the bracket and coöperating with the rotor; a slide supported for reciprocation on the standard; an arm connecting the slide with the plunger; a ribbon movable between the plunger and the rotor; and feeding mechanism for the ribbon, the feeding mechanism being operatively connected to the slide. 75

2. In a device of the class described, a 80 frame comprising a standard having a forwardly presented bracket and provided with a rearwardly extended lug located at the 85 juncture between the standard and the bracket; a type-carrying rotor journaled on the standard below the bracket; a plunger slideable in the bracket and coöperating with the rotor; a slide mounted to reciprocate in the lug; an arm connecting the slide with the plunger; a ribbon movable between the plunger and the rotor; and feeding mechanism for the ribbon, the feeding mechanism being operatively connected to the 90 slide. 95

3. In a device of the class described, a 100 frame; a type-carrying rotor journaled in the frame; a plunger mounted to reciprocate in the frame and coöperating with the 105 rotor; shafts journaled in the frame; a ribbon wound about the shafts and extended between the plunger and the rotor; ratchet wheels on the shafts; levers fulcrumed on the frame; pawls carried by the levers and 110 coöperating with the ratchet wheels; means for holding either pawl out of engagement with the corresponding ratchet wheel; a slide mounted to reciprocate in the frame and connected to the levers; and means for 115 connecting the slide with the plunger. 120

4. In a device of the class described, a 125 base; a standard carried by the base; a dial carried by the base; a shaft journaled in the standard and in the dial; a type-carrying rotor mounted on the shaft and located between the standard and the dial; a plunger mounted to reciprocate in the standard and coöperating with the rotor; an arm secured to the shaft and movable over the dial; and a resilient latch mounted on the arm, the dial having a forwardly presented annular flange provided with seats for the reception of the latch. 130

5. In a device of the class described, a 125 base; a standard carried by the base; a dial carried by the base; a shaft journaled in the standard and in the dial; a type-carrying rotor mounted on the shaft and located between the standard and the dial; a plunger 130

mounted to reciprocate in the standard and coöperating with the rotor; an arm secured to the shaft and movable over the dial; and a resilient latch mounted on the arm, the dial being provided with seats for the reception of the latch.

5 In testimony that I claim the foregoing

as my own, I have hereto affixed my signature in the presence of two witnesses.

SAMUEL D. McMILLAN.
